UNITED STATES PATENT OFFICE.

JASON B. MOODY, OF DALLAS, TEXAS.

CHECK AND THE LIKE.

1,291,077.

Specification of Letters Patent. Patented Jan. 14, 1919.

Application filed October 6, 1916, Serial No. 124,020. Renewed June 10, 1918. Serial No. 239,276.

To all whom it may concern:

Be it known that I, JASON B. MOODY, citizen of the United States, residing at Dallas, in the county of Dallas and State of Texas, have invented certain new and useful Improvements in Checks and the like, of which the following is a specification.

This invention relates to new and useful improvements in checks and the like and particularly to a universal check.

The object of the invention is to provide a check bearing the names of a number of banks, departments or similar designations and arranged so that the check can be drawn or charged to any particular one of the banks, departments or designations, thus making one style of check serve of the purpose of several.

Another object of the invention is to provide a check or the like having a number of designations indicating banks or departments, with a number associated with each designation, and a place to write the number of the designation against which the check is drawn.

A still further object of the invention is to provide a check of the character described that will be efficient, simple, and inexpensive to produce.

With the above and other objects in view the invention has relation to certain novel features of construction and operation, an example of which is described in the following specification and illustrated in the accompanying drawings, wherein:

Figure 1 is a face view of the check,

Fig. 2 is a similar view showing the check drawn on one of the banks, and

Fig. 3 is a face of modified form.

In the drawings the letter A designates a check which has the usual date line B along its upper edge portion. At the central portion of the check lines C and D are provided for writing the name of payee and the amount. Along the lower edge portion a signature line E is printed.

To the left of these lines panels F, G, H and I are disposed in the order named. The panels F and H are duplicates and have printed therein numbers disposed in vertical order, the numbers of each being duplicates and horizontally alined. The names of the banks are printed in the panel G, a bank name being alined with each pair of duplicate numbers.

The panel I may have any desirable legend

printed therein and may be omitted entirely if desired. At the right hand end of the check and between the lines B and C a designating number panel J is provided and associated with this panel are suitable printed instructions telling how to make out the check. It will be noted that each bank name is associated with a number, which may be arbitrary or which may be the clearing house number. Directions are given to write the number of the bank desired, in the number designating panel J and to draw a ring around the bank name in the panel G. The bank number being associated with the bank name enables one to readily know what it is, and making a ring around the name double checks the designation of the bank desired by the party drawing the check.

In using the check the date, number, amount and name of the payee are written in as shown in Fig. 2, and the check signed. After this is done the party drawing the check draws a ring around the name of the bank handling his account, and then writes the bank number in the panel J. In Fig. 2 the "Second National Bank" is drawn on and the number for this bank being "5," it is written in the panel J.

It is obvious that in places where pads of checks of different banks in a city are kept for the use of patrons, a constant supply is required and much time is lost going to the different banks to get checks. The check herein set forth will serve for all the banks in a city and will be a great convenience as only one style of check need be supplied.

The names need not be of banks located all in the same city or place, but may be associated banks or banks in the same community.

It will be understood that this invention is not limited to bank checks and that it may be applied to different forms of negotiable instruments. In Fig. 3 I have shown a check M having all of the panels and lines of the check A, except the panel I, the same reference letters being employed. This form is a credit check for use in a department store and in the panel G the names of the departments are printed, while in the panels F and H, the department numbers are arranged. An additional line S is printed on this form for writing in the name of the goods returned.

The check S is shown made out for the return of a pair of shoes and drawn for \$2.50

against the shoe department which is designated by its number, 7. It is to be understood that the check M may be arranged for a greater number of departments and many deviations may be made.

5 The salient feature of this invention is a universal check bearing the names of associated banks, etc., each designated by a number or other symbol, and the provision of a 10 space on the check for writing in the number of the bank, etc., against which the check is drawn.

What I claim, is:

15 1. A negotiable instrument having provision for writing thereon the name of the payee, the amount and the signature of the maker; also having printed thereon associated designations each accompanied by a symbol; said instrument also having a blank 20 panel for the writing of the symbol of the particular designation against which the instrument is drawn.

25 2. A negotiable instrument having provision for writing thereon the name of the payee, the amount and the signature of the maker; also being printed with a panel containing names and having an adjacent panel printed with numbers, each number being associated with a name; and said instrument 30 also having a blank panel for writing in the number of the bank on which the instrument is drawn.

30 3. A negotiable instrument having provision for writing thereon the name of the

payee, the amount and the signature of the 35 maker; also being printed with a panel containing the names of associated banks and having an adjacent panel printed with numbers, each bank name being associated with one of the numbers; and said instrument also 40 having printed thereon a bank number designating panel normally blank and in which the number of one of the bank names is written.

4. A universal bank check having provision 45 for writing the usual matter thereon, and also being printed with the names of associated banks and a distinguishable symbol correlated with each bank name, and having also a panel provided for the writing 50 therein of one of the symbols whereby the bank on which the check is drawn is designated.

5. A universal bank check having provision 55 for writing the usual matter thereon; also having a panel printed with the names of associated banks and another panel correlated therewith printed with numbers, a number being assigned to each bank name; and also having a blank designating panel 60 isolated from the other panels and in which the bank number is written.

In testimony whereof I affix my signature in presence of two witnesses.

JASON B. MOODY.
